UNITED STATES PATENT OFFICE.

JOHN C. YOUNG AND GEORGE A. DAVIS, OF NEENAH, WISCONSIN.

SUCTION-BOX FOR PAPER-MAKING MACHINES.

SPECIFICATION forming part of Letters Patent No. 426,089, dated April 22, 1890.

Application filed October 19, 1889. Serial No. 327,597. (No model.)

To all whom it may concern:

Be it known that we, JOHN C. YOUNG and GEORGE A. DAVIS, citizens of the United States, residing at Neenah, in the county of Winnebago and State of Wisconsin, have invented a new and useful Improvement in Suction-Boxes for Paper-Making Machines, of which the following is a specification.

Our invention relates to improvements in a suction device over which the wire of a paper-machine is carried upon a perforated cylinder, said cylinder being so constructed and arranged in position with relation to other parts of the machinery as to constitute a combined suction, wire-driving, and couch roll; and the object of our improvement is to lessen the wear of the wire and produce a suction device that will effectually remove moisture from the pulp while upon said wire. We attain these objects by the mechanism illustrated in the accompanying drawings, in which—

Figure 1 is an end elevation of the device, consisting of a perforated cylinder carrying the wire of the paper-machine, showing its arrangement upon a paper-machine frame, a part of the standard which supports said cylinder being represented in dotted lines, so as not to obscure parts the illustration of which is deemed more essential, also showing the wire, one of the dekle-drums, a part of one of the dekle-straps thereon, the dandy-roll, one of the felt-rolls, and the felt thereon. Fig. 2 is an end view, upon a reduced scale, of the suction-boxes, the cylindrical shell thereon, and showing a side of one of the brackets which support the suction-boxes, the support for the cylinder and for the shaft carrying said bracket being omitted. Fig. 3 is a longitudinal section of that part containing the suction-boxes, (a part of its central portion lengthwise being broken away for the purpose of its representation upon a scale permitting a clear illustration of its parts,) a part of its length being an elevation of its delivery side, showing the paper, the perforations in a part of the revolving cylinder, a part having the cylinder covered with the wire, and its other portions being in section taken upon the line *xx* of Figs. 1 and 2, as seen in looking toward the left. Fig. 4 is a detail showing a longitudinal section upon the line *yy* of Fig.

2, upon the like scale as Fig. 1, of a part of one of the sides of the suction-boxes.

Similar letters of reference indicate like parts in the several views.

A is the machine-frame; B, a perforated hollow cylinder; B', a head therefor; B'', a journal extended from the head of said cylinder; C, a box for said journal; C', a box-standard at the other end of the cylinder; C'', a set-screw in said box; D, a gear-wheel; E, a shaft; F, a felt-roll; F', the felt thereon; G, a dekle-drum; G', the dekle-strap thereon; H, the wire of the paper-machine; H', the paper; a, friction-wheels; a', a spider carrying upon the ends of its arms said wheels; b, a series of small holes formed in the shell of the cylinder B; c, brackets upon the shaft E; d d', suction-boxes on said brackets; d'', grooves in the sides of said boxes; e e', pipes leading from the boxes d and d', respectively; f f', screw-rods which operate the suction-box heads; g, flanges forming the suction-box heads; g', a sheet of india-rubber interposed between the flanges g; h, strips of wood inserted in the grooves d'; h', springs under said strips; i, an air-blast pipe; j, a showering-pipe.

In the arrangement of our combined suction, wire-driving, and couch roll we mount the perforated cylinder B for revolution, it having in one end the head B', said head being provided with the journal B'', which revolves in the journal-box C, the extremity of said journal being provided with the gear-wheel D, by which the cylinder may be revolved by any available motor. The opposite end of the cylinder is open and is supported for revolution upon a series of friction-wheels a, said wheels being mounted for revolution upon the arms of the spider a', the spider being secured to the shaft E, and said shaft being inserted one end in the head B' of the cylinder and the other end in the box-standard C'. The shaft is secured in said standard against rotation by means of the set-screw C'', thereby permitting the cylinder to revolve around the aforesaid spider upon the wheels a.

The friction-wheels a are made adjustable nearer to or farther from the center of the shaft E, thereby providing for their wear and their easy insertion into and removal from

said cylinder. This may be accomplished in any convenient manner, and is represented in the present case as being held in the desired position by means of the set-screw *a''*.

5 The cylinder is represented in Fig. 3, where a portion of its surface is shown as having said surface pierced with a large number of small holes *b*. In practice these holes should be one-eighth of an inch in diameter and be 10 five-sixteenths of an inch from center to center (a little more or less may be as effectual) and cover the surface of the cylinder the full width of the wire *H*.

At several points in the length of the shaft 15 *E*, and firmly secured thereto, are brackets *c*, which support the suction-boxes *d d'*, each compartment being connected by a separate pipe *e* and *e'* to the suction-producing power. The pieces composing the suction-boxes or 20 the lengthwise channels are secured to the brackets *c* with screws or bolts, and can be quickly removed for repairs or renewal.

Within each of the compartments *d d'* are arranged longitudinally thereof rods *f f'*, each 25 one having upon one end of it a right-hand and upon its opposite end a left-hand thread, and carrying upon each of said threaded portions heads *g*, movable thereon for the purpose of adapting the width of the working 30 part of the suction-boxes to the width of the web of paper passing over them. By the turning of the rods *f f'* by means of cranks or their handles *f''* the heads *g* are moved nearer to or farther from each other, and 35 thereby adapting the suction-space to the width of the paper.

The rods *f f'* may each consist of two pieces and be operated separately, if desired, their threads not necessarily then being a right 40 and left one. The plan shown is, however, the one we prefer.

The heads *g* are formed of two metallic flanges threaded internally and fitting upon the threaded portion of the rods, each pair 45 of flanges having clamped between them a thick sheet of india-rubber *g'*, for the purpose of producing an air-tight joint between the heads and sides of said boxes.

A longitudinal section upon the line *y y* of 50 Fig. 2, upon the scale of Fig. 1, of a part of the side of a suction-box is shown in Fig. 4. A channel *d''*, as shown in the end view, is cut in each side of said boxes, which sides are preferably made of metal, into which a strip 55 of wood *h* is inserted, and having under each strip numerous springs *h'*, which are for the purpose of securing air-tight joints between the sides of said boxes and the interior surface of the perforated cylinder. These springs 60 are shown in Fig. 4 as being formed of a thin strip of steel; but coiled wire or india-rubber ones may be made equally effective.

The suction-boxes can be removed from the cylinder *B* for repairs, &c., by first disconnecting the pipes *e e'*, blocking up the open end of the cylinder, and removing the box-standard *C'*, which is removably attached to

the frame *A*, when the shaft *E*, with the spider and friction-wheels, the brackets *c*, and suction-boxes, can be withdrawn from the cylinder. 70

The wire *H* covers the cylinder and the perforations therein, and as the paper in its formation is carried along over said perforations, when it is over either compartment of the suction device it is subjected to their powerful suction. The degree of said suction and the compartment through which is applied said suction are under the control of the attendant by means of the necessary cocks which are 80 applied to the pipes leading from each compartment.

We do not confine our invention to the exact location here shown for said boxes, as we may separate the two boxes, leaving a space 85 between them, over which we may place the dandy-roll, which is here shown as being over the upper suction-box, or we may increase the number of said boxes and let them extend over more of the interior surface of the cylinder. 90

At a point within the cylinder *B*, near its front lower portion and longitudinally thereof, is arranged a pipe *i*. It may be suspended from the shaft *E* or brackets *c* at the closed end of said cylinder, and having upon its lower side a line of fine holes, or preferably longitudinal slits, through which a blast of air can be thrown, said pipe being provided with a gate or cock by which said blast can 100 be governed. This device is made use of in starting up the machine in the delivery of the sheet of paper from the cylinder to the felt *F'*. As the sheet of paper passes down over the cylinder upon the wire, when opposite this 105 pipe, the air-blast is applied, which detaches the paper from the wire and delivers it to the roll *F*, where it is caught by the felt and carried onward without the necessity of an attendant to make the transfer and without the 110 usual loss of material in making it. In the rear of the cylinder and above the lower wire *H* is a pipe similarly arranged and operated, but having instead of air a spray of water ejected therefrom. The purpose of this is 115 for showering and cleaning the wire.

The dekle-drum *G*, carrying the dekle-strap *G'*, is arranged directly above the cylinder *B* in the position relative to it that the upper couch-roll usually occupies relative to 120 the lower one.

The dandy-roll *I* we have placed upon the wire over the upper compartment of the suction-boxes; but a different location for it may sometimes be used.

It is evident that the perforated cylinder with the suction device herein described is adapted for use in a paper-machine in front of the usual couch-roll in or near the location in which the stationary suction-boxes of a 130 paper-machine are usually placed, and also that it may be used as one of the rolls on which the felt is carried, all of which we consider as within the scope of our invention. 125

Having described our invention, what we claim, and desire to secure by Letters Patent, is—

1. A suction device for a paper-making machine, comprising a perforated cylinder having one open end, said cylinder being provided upon its opposite end with a journal and being revoluble thereon, the open end of the cylinder being arranged to revolve upon a series of friction-wheels, a non-rotative shaft, one end thereof being supported inside of said cylinder, in the journaled end thereof, the other upon the frame of said machine, said shaft having one or more suction-boxes supported thereon, and around which said perforated cylinder is adapted for revolution, substantially as described.
2. In combination with the wire of a paper-making machine, a suction device comprising a perforated cylinder having one open end, said cylinder being provided upon its opposite end with a journal and being revoluble thereon, the open end of the cylinder being arranged to revolve upon a series of friction-wheels, a non-rotative shaft, one end of said shaft being supported inside of said cylinder, in the journaled end thereof, the other upon the frame of said machine, said shaft having one or more suction-boxes supported thereon, and around which said perforated cylinder is adapted for revolution, substantially as described.
3. In combination with the wire of a paper-making machine, a suction device comprising a perforated cylinder having one open end, said cylinder being provided upon its opposite end with a journal and being revoluble thereon, the open end of the cylinder being arranged to revolve upon a series of friction-wheels, a non-rotative shaft, one end thereof being supported inside of said cylinder, in the

journaled end thereof, the other upon the frame of said machine, said shaft having one or more suction-boxes supported thereon and around which said perforated cylinder is 45 adapted for revolution, each box comprising a channel lengthwise of said shaft, an outlet from each channel, heads movable longitudinally thereof, and means, substantially as described, for adjusting said heads to register 50 with the line of contact of the paper upon the wire carried by said cylinder, substantially as described.

4. In a paper-making machine, the combination of a perforated revoluble cylinder, the 55 wire thereon, a stationary suction-box within said cylinder, the air-blast pipe *i*, means for producing a pressure of air therein and for controlling the degree of said pressure, and openings in the pipe for the escape of said air, 60 the pipe being adapted in position within said cylinder, whereby the escaping air may be directed through the perforations of said cylinder and the wire for the purpose of detaching the paper from the wire and for its delivery to the felt upon the felt-rolls of said 65 machine, substantially as described.

5. In a suction device for a paper-making machine, the combination of a perforated revoluble cylinder, one or more stationary longitudinal channels around which said cylinder revolves, the grooves *d''*, strips *h* and springs *h'* therein, screw-threaded rods longitudinally of said channels, flanges *g g*, movable thereon, and the india-rubber sheets *g'* between said 75 flanges, substantially as described.
